UNITED STATES PATENT OFFICE.

CALVIN LUTHER IUNGERICH, OF HARRISBURG, PENNSYLVANIA, ASSIGNOR
OF ONE-THIRD TO WILLIAM S. REEL AND ONE-THIRD TO SAMUEL O.
REEL, OF HARRISBURG, PENNSYLVANIA.

AUTOMATIC STOP-SIGNAL SYSTEM.

No. 841,403.

Specification of Letters Patent.

Patented Jan. 15, 1907.

Application filed September 1, 1906. Serial No. 332,980.

To all whom it may concern:

Be it known that I, CALVIN LUTHER IUNGERICH, a citizen of the United States, residing at Harrisburg, in the county of Dauphin and State of Pennsylvania, have invented a new and useful Automatic Stop-Signal System, of which the following is a specification.

This invention relates to mechanism for automatically applying the air-brakes on a train of cars in case the engineer should for any reason fail to notice a danger-signal or attempt to run the train past a signal-block.

The object of the invention is to provide means operable through the medium of suitable actuating devices along the track for automatically applying the brakes when the semaphore-arm is moved to caution or danger position, thus effectually stopping the train without attention on the part of the engineer.

A further object is to provide means for disconnecting the valve-operating means, thereby to permit the brake-valve to be moved to released position.

25 A further object is to provide gravity-actuated means for automatically shifting the valve to lap position after each application of the brakes, and means whereby the valve may be operated independently of the automatic means.

A still further object is to generally improve this class of devices so as to increase their utility, durability, and efficiency.

With these and other objects in view the invention consists in the construction and novel combination and arrangement of parts hereinafter fully described, and illustrated in the accompanying drawings, it being understood that various changes in form, proportions, and minor details of construction may be resorted to within the scope of the appended claims.

In the accompanying drawings, forming a part of this specification, Figure 1 is a side elevation of an air-brake signal apparatus constructed in accordance with my invention. Fig. 2 is a side elevation showing the construction of the track devices. Fig. 3 is a top plan view of one of the track devices. 50 Fig. 4 is a top plan view of the engineer's brake-valve. Fig. 5 is a side elevation of the same.

Similar numerals of reference indicate cor-

responding parts in all of the figures of the drawings.

5 In the accompanying drawings, 5 designates the track, upon which is mounted for travel a locomotive 6 of any approved construction, in the cab 7 of which is positioned the engineer's brake-valve 8. The valve 8 is 60 provided with the usual operating-lever 9, and extending laterally from the pivoted end of said lever is a flange or plate 10, having a slot or recess 11 formed therein and opening through the periphery of the flange, as shown. 65 Extending from the valve-casing at the upper end thereof are spaced arms 12, connected by a longitudinally-disposed bar 13 and defining a slot or guideway 14 for the reception of a sliding block or cross-head 15. The bar 13 70 is detachably secured to the arms 12 by screws or similar fastening devices 16, whereby the cross-head 15 may be readily removed from or positioned within the guideway 14.

75 Pivottally mounted on the block 15 is a pawl 17, one end of which is provided with a threaded extension 18, which extends through the block or cross-head 15, while the opposite end thereof is provided with a depending lug 19, adapted to enter the slot 11 for moving the valve to operative and inoperative position. Pivottally mounted on the extension 18 and secured thereto by a clamping-nut 20 is a link 21, the opposite end of which is pivotally connected to a vertically-reciprocating rod 22, which extends through a tube or guiding member 23 and is provided with a terminal weight or knob 24, constituting a tappet adapted to engage the track devices or cams, as will be more fully explained hereinafter. The guide 23 is secured in position by lateral braces 25, secured in any suitable manner to the walls of the cab 7, there being an auxiliary guide 26 arranged within the cab near the engineer's valve, as 95 shown. Extending laterally from the valve-casing and secured thereto in any suitable manner, as by screws 27, is a bracket 28, the free end of which is bent upwardly to form a yieldable arm 29, having an inclined or cam 100 face 30, adapted to engage the correspondingly-inclined face 31 of the pawl 17, the latter being provided at its free end with a curved or rounded surface 32. It will thus be seen that when an upward pull is exerted 105 on the rod 22 the cross-head 15, through the

medium of the link 21, will move the pawl 17 laterally, and thus rotate the handle 9 to service position and apply the brakes.

As the pawl is moved laterally by the rod 22 the curved end 32 of the pawl will engage the inclined face 30 and depress the arm 29 laterally to permit the passage of said pawl, the arm 29 automatically returning to normal position in engagement with the inclined face 31 of the pawl as soon as the latter has cleared said arm. When the upward pressure on the rod 22 is released, the weight 24 will, through the medium of the pawl 17, return the lever 9 to lap position, thus holding the brakes applied. The initial rearward movement of the pawl 17 will cause the inclined face 30 to engage the inclined face 31, so that after the lever 9 has been moved to lap position the lug 19 will be lifted out of the slot 11 and in position to again engage the slot 11 when the tappet is again actuated to apply the brakes.

The pawl 17 is provided with a handle or finger-piece 33, by means of which the pawl 17 may be manually lifted out of the slot 11, thereby to permit the engineer to operate the lever 9 independently of the automatic means.

As a means for automatically operating the engineer's brake-valve there is provided one or more stationary tappets or cams disposed at predetermined intervals along the track 5 and each consisting, preferably, of a plate 34, the opposite ends of which are deflected downwardly and connected to the cross-ties 35 by suitable coil-springs 36.

Disposed in alignment with the apex of each of the tappets or plates 34 and secured in any suitable manner to the adjacent cross-tie 35 are spaced brackets 36', in which is journaled a stub-shaft 37, one end of which is provided with a crank-arm 38, while the opposite end thereof is provided with a lifting member or arm 39, adapted to engage the adjacent wall of the plate 34 and elevate the same above the track-rails when the lifting device 39 is moved to operative position.

Arranged on one side of the track and spaced at any desired distance from the adjacent cam or track device 34' is a post or standard 40, on the upper end of which is pivotally mounted a semaphore-arm 21, the latter being provided with a crank-arm 42, to which is secured a cord or cable 43. The cable 43 passes over suitable pulleys or rollers 44 and 45 and is thence extended laterally to the signaling-tower and operatively connected with the switch-lever.

Secured to the cable 43 is an auxiliary cable 46, which extends substantially parallel with the rails 5 and is connected to the crank-arms 38 of the stub-shafts 37, so that when the lever in the signaling-tower is moved to elevate the semaphore-arm 21 to caution or danger position the cable 46 will actuate one or the other of the lifting devices 39, and thus

project the cams or plates 34 and 34' above the adjacent surface of the track and in the path of movement of the knob or tappet 24.

The elevating devices 39 are so positioned on the shafts 37 that when the danger-signal is displayed at the semaphore-arm the cam or track device 34 will be elevated so as to actuate the tappet 24 and move the lever of the brake-valve to service position, while the tappet or plate 34' will be elevated above the track a sufficient distance to cause the tappet 24, through the medium of the rod 22, to rotate the lever to emergency position. When the caution-signal is displayed at the signal-arm, however, the cam or plate 34' is not affected, while the tappet or plate 34' will be projected a sufficient distance above the track to move the brake-valve to service position.

The operation of the device is as follows: Should the operator in the signal-tower throw the switch-lever so as to display "danger" at the semaphore-arm, the cams or tappets 34 and 34' will be elevated to operative position above the track and in the path of movement of the knob or tappet 24. As the train approaches the signal-station the knob or tappet 25 will ride over the inclined surface of the cam and through the medium of the rod 22 and pawl 17 move the valve-lever 9 to service position, the weight of the knob 24 automatically returning the lever 9 to lap position as soon as the knob 24 is disengaged from or passes the cam 24, thus applying a service application of the brakes and warning the engineer of danger ahead. Should the engineer after receiving the first warning fail to release the pawl 17 and apply the emergency-brakes, the locomotive in its forward movement will cause the tappet 24 to engage the inclined face of the cam 34', thus elevating the rod 22 a greater distance, and thereby causing the pawl 17 to move the brake-lever 9 to emergency position. As soon as the tappet 24 clears the cam 34' the weight of the knob will automatically return the lever to lap position, thus holding the emergency-brakes applied and effectually stopping the car without attention on the part of the engineer.

It will here be explained that the action of the pawl 17 when the brake-lever is moved to emergency position is exactly the same as when said lever is moved to service position, the only difference being the extent of movement of the pawl, in both cases the pawl being automatically lifted out of the slot 11 and the lever 9 returned to lap position after each application of the brakes. When it is desired to operate the engineer's valve independently of the automatic means, the pawl 17 is lifted from the slot 11 by exerting an upward pull on the finger-piece 33, thus permitting the engineer to move the lever 9 and apply the brakes independently of the automatic means.

From the foregoing description it is thought that the construction and operation of the device will be readily understood by those skilled in the art, and further description 5 thereof is deemed unnecessary.

Having thus described the invention, what is claimed is—

1. An air-brake apparatus including an engineer's brake-valve, a track device, means 10 operable by the track device for moving the valve to brake position, and means for automatically shifting the valve to lap position when the valve-operating means is released.

2. An air-brake apparatus including an engineer's brake-valve, a track device, means 15 operable by the track device for automatically moving the valve to brake position, and gravity-actuated means for shifting the valve to lap position when the valve-operating means is released.

3. An air-brake apparatus including an engineer's brake-valve, a track device, means 20 operable by the track device for automatically moving the valve to brake position, means for shifting the valve to lap position when the valve-operating means is released, and means for operating the valve independently of the automatic means.

4. An air-brake apparatus including an engineer's brake-valve, a track device, means 25 operable by the track device for automatically moving the valve to brake position, means for shifting the valve to lap position when the valve-operating means is disengaged 30 from the track device, and means for disconnecting the valve-operating means from said valve.

5. An air-brake apparatus including an engineer's brake-valve, a track device, a pawl 40 operatively connected with the valve and actuated by the track device for moving the valve to brake position, and means for shifting the valve to lap position.

6. An air-brake apparatus including an engineer's brake-valve, a track device, a pawl 45 operatively connected with the valve, means depending from the pawl and extending in the path of movement of the track device for moving the valve to brake position, and means for moving the valve to lap position, when the track-engaging means is released.

7. An air-brake apparatus including an engineer's brake-valve, a track device, a pawl 55 operatively connected with the valve, a tappet carried by the pawl and adapted to engage the track device for moving the valve to brake position, said tappet being weighted thereby to shift the valve to lap position when the tappet is disengaged from the track device.

8. An air-brake apparatus including an engineer's brake-valve, a track device, a pawl 60 operatively connected with the valve, a tappet depending from the pawl and adapted to engage the track device for moving the valve

to brake position, gravity-actuated means for shifting the valve to lap position when the tappet is disengaged from the track device and means for disconnecting the pawl from the valve thereby to permit the valve to be 70 operated independently of the automatic means.

9. An air-brake apparatus including an engineer's brake-valve, a guide secured to the casing of the valve, a cross-head slidably 75 mounted in the guide and operatively connected with the valve, a track device, a tappet depending from the cross-head and adapted to engage the track device for moving the valve to brake position, and means for automatically shifting the valve to lap position when the tappet is disengaged from the track device.

10. An air-brake apparatus including an engineer's brake-valve, a track device, means 80 operable by the track device for automatically moving the valve to service or emergency position, and gravity-actuated means for shifting the valve to lap position when the valve-operating means is disengaged from 85 the track device.

11. An air-brake apparatus including an engineer's brake-valve, a guide, a cross-head 90 slidably mounted on the guide, a pawl pivotally mounted on the cross-head and adapted 95 to engage a slot in the valve, a track device, a tappet depending from the cross-head and adapted to engage the track device for shifting the valve to service or emergency position, said tappet being weighted thereby to 100 automatically shift the valve to lap position when the tappet is disengaged from the track device.

12. An air-brake apparatus including an engineer's brake-valve, a plurality of track 105 devices movable alternately to operative position, means operatively connected with the valve for moving the latter to service position when the valve-operating means engages one of the track devices, said valve being moved to emergency position when the operating means engages the opposite track device, and gravity-operating means for automatically returning the valve to lap position 110 after being disengaged from the track device.

13. An air-brake apparatus including an engineer's brake-valve, a plurality of track 120 devices movable successively to operative position, a pawl operatively connected with the valve, a tappet depending from the pawl and extending in the path of movement of the track devices for moving the valve to service position when the tappet engages one of said track devices, said valve being moved to 125 emergency position when the tappet engages the opposite track device, and means carried by the tappet for automatically returning the valve to lap position after each application of the brakes.

14. An air-brake apparatus including an engineer's brake-valve, a signal, track devices operatively connected with the signal, means operated by the track device for moving the valve successively to service and emergency position when different signals are displayed, and gravity-actuated means for automatically returning the valve to lap position after each application of the brakes.
15. An air-brake apparatus including an engineer's brake-valve, spring-pressed track devices, a signal operatively connected with the track devices for successively moving the track devices to operative position when different signals are displayed, a pawl operatively connected with the brake-valve, a tappet depending from the pawl and adapted to engage the track devices for moving the brake-valve successively to service and emergency position, means for returning the valve to lap position when the tappet is disengaged from the track devices, and means for disconnecting the pawl and valve thereby to permit the operation of the valve independently of the automatic means.
16. An air-brake apparatus including an engineer's brake-valve, spring-pressed track devices having cam-faces, lifting-arms for moving the track devices to operative position, a signal, a flexible medium connecting the lifting device with the signal, means operatively connected with the valve and adapted to engage the track devices for moving the valve to brake position, and gravity-actuated means for automatically returning the valve to lap position after each application of the brakes.
17. An air-brake apparatus including an engineer's brake-valve, a yieldably-supported track device having operatively-disposed cam-faces, a stub-shaft having a crank-arm at one end thereof and lifting-arm at the other for elevating the track device to operative position, a signal, a connection between the signal and the crank-arm, means operatively connected with the valve and adapted to engage the track device for moving the valve to brake position, and means for automatically returning the valve to lap position when the valve-operating means is disengaged from the track device.
18. An air-brake apparatus including an engineer's brake-valve, a pawl adapted to engage a slot in the valve, a track device, means connected with the pawl and adapted to engage the track device for moving the valve to brake position, means for automatically returning the valve to lap position, and a cam extending in the path of movement of the pawl for releasing the latter from the slot when the valve is returned to lap position.
19. An air-brake apparatus including an engineer's brake-valve, a pawl adapted to engage a slot in the valve, a track device, a tappet depending from the pawl and adapted to engage the track device for moving the valve to brake position, means for automatically returning the valve to lap position, and a cam extending in the path of movement of the pawl for releasing the latter from the slot when the valve is returned to lap position.
20. An air-brake apparatus including an engineer's brake-valve, a guide, a cross-head slidably mounted in the guide, a pawl pivotally mounted on the cross-head and adapted to engage a slot in the valve, the free end of the pawl being provided with an inclined face, a track device, a tappet pivotally mounted on the cross-head and adapted to engage the track device for moving the valve to brake position, a cam yieldably supported in the path of movement of the pawl, means for automatically returning the valve to lap position, said cam being adapted to engage the inclined face of the pawl for disengaging the latter from the slot in the valve when the valve is moved to lap position.
21. An air-brake apparatus including an engineer's brake-valve, a guide, a cross-head slidably mounted in the guide, a pawl pivotally mounted on the cross-head and adapted to engage a slot in the valve, the free end of said valve being rounded and provided with an inclined face, a track device, a link pivoted to the cross-head, a tappet pivoted to the link and adapted to engage the track device for moving the valve to brake position, a yieldable arm provided with a cam-face adapted to engage the curved end of the pawl when the valve is moved to brake position, means for moving the valve to lap position, said cam being adapted to engage the inclined face of the pawl for disengaging the latter from the slot when the valve is moved to lap position.
22. An air-brake apparatus including an engineer's brake-valve, a flange extending laterally from the lever of the valve and provided with a slot, a guide, a cross-head slidably mounted in the guide, a pawl pivotally mounted on the cross-head and adapted to engage the slot, a track device, a tappet operatively connected with the cross-head and adapted to engage the track device for moving the valve to brake position, means for returning the valve to lap position, and a cam yieldably supported in the path of movement of the pawl for disengaging the latter from the slot in the flange when the valve is moved to lap position.
23. An air-brake apparatus including an engineer's brake-valve, a flange extending laterally from the valve and provided with a slot, a guide, a cross-head slidably mounted in the guide, a pawl pivotally mounted on the cross-head and having its free end round-

- ed and provided with a depending lug adapted to engage a slot in the flange, said pawl being provided with an inclined face disposed at said lug, a track device, a tappet depending from the cross-head and adapted to engage the track device for moving the valve to brake position, a cam yieldably supported in the path of movement of the pawl and adapted to be moved laterally by engagement with the curved face of the pawl when the valve is moved to brake position, means for shifting the valve to lap position, said cam being adapted to engage the inclined face of the pawl for disengaging the lug from the slot in the flange when the valve is moved to lap position.
24. An air-brake apparatus including an engineer's brake-valve, a flange extending laterally from the operating-lever and provided with a slot, a guide, a cross-head slidably mounted in the guide a pawl pivotally mounted on the cross-head and adapted to engage the slot, a track device, a link pivoted to the cross-head, a tappet pivoted to the link and adapted to engage the track device for moving the valve to brake position, said tappet being weighted thereby to automatically move the valve to lap position when the tappet is disengaged from the track device, and a finger-piece carried by the pawl for disengaging the latter from the slot in the flange.
25. An air-brake apparatus including an engineer's brake-valve, a flange extending laterally from the lever of the valve and provided with a slot, arms extending vertically from the valve-casing and connected by a detachable bar forming a guide, a cross-head slidably mounted in the guide, a pawl pivotally mounted on the cross-head and adapted to engage the slot, a link secured to the cross-head, a track device, a tappet secured to the opposite end of the link and adapted to engage the track device for moving the valve to brake position, said tappet being weighted thereby to automatically return the valve to lap position when the tappet is disengaged
- from the track device, and means for manually disengaging the pawl from the slot in the valve thereby to permit the latter to be operated independently of the automatic means.
26. An air-brake apparatus including an engineer's brake-valve, means for automatically moving the valve to brake position, and means for automatically shifting the valve to lap position when the valve-operating means is released.
27. An air-brake apparatus including an engineer's brake-valve, means for automatically moving the valve to brake position, means for automatically shifting the valve to lap position when the valve-operating means is released, and means for operating the valve independently of the automatic means.
28. An air-brake apparatus including an engineer's brake-valve, means for automatically moving the valve to service or emergency position, and means for shifting the valve to lap position when the valve-operating means is released.
29. An air-brake apparatus including an engineer's brake-valve, a signal, means operatively connected with the signal for moving the valve to brake position when a signal is displayed, and means for automatically returning the valve to lap position after the valve-operating means is released.
30. An air-brake apparatus including an engineer's brake-valve, a signal, means operatively connected with the signal for moving the valve successively to service and emergency position when different signals are displayed, and means for automatically returning the valve to lap position after each application of the brakes.
- In testimony that I claim the foregoing as my own I have hereto affixed my signature in the presence of two witnesses.
